(57) **CLAIM**

I claim the ornamental design for a skimmer net, as shown and described.

DESCRIPTION

FIG. 1: is a Perspective view for a skimmer net according to my new design;

FIG. 2: is a Front plan view thereof;

FIG. 3: is a Back plan view thereof;

FIG. 4: is a Left elevation view thereof;

FIG. 5: is a Right elevation view thereof;

FIG. 6: is a Top view thereof; and,

FIG. 7: is a Bottom view thereof, showing my design.

1 Claim, 7 Drawing Sheets
